UNITED STATES PATENT OFFICE.

HERBERT T. SNYDER, OF NEW YORK, N. Y., ASSIGNOR TO UPRESSIT PRODUCTS CORPORATION, OF NEW YORK, N. Y., A CORPORATION OF NEW YORK.

RECEPTACLE CLOSURE.

Application filed December 29, 1921. Serial No. 525,609.

This invention relates to closures for bottles or similar containers. One object of this invention is to lock said closures against accidental opening, and to insure that 5 fraudulent opening will be betrayed.

More particularly, this invention relates to closures of the type disclosed in the Spengler Patent No. 1,074,907, in which gripping fingers are movable to effective or 10 ineffective positions to grip or release the container to which it is applied, this invention providing means for preventing movement of said fingers to unlocking position.

A further feature of this invention is the 15 construction of the locking means so that any tampering or fraudulent unlocking will be readily betrayed.

Other features and advantages will herein- 20 after appear.

In the accompanying drawings:

Figure 1 is a plan view of the closure and the locking device therefor applied to a container, the open or ineffective position of the locking device being shown in dotted lines;

Figure 2 is a vertical section of the structure shown in Figure 1;

Figure 3 is a section on the line 3—3 of Figure 4 of a detail showing the fastening member of the locking device;

Figure 4 is a view, partly sectioned and in front elevation;

Figure 5 is a detail showing the gripping fingers of the closure member.

The Patent No. 1,074,907, noted above, describes a closure for a container such as a bottle, said closure comprising a disk 10 resting near its periphery at 12 upon the upper edge of the container and having a downwardly extending flange formed into gripping fingers 11 by slits such as 15. The disk 10 of the closure is larger than the opening which it covers so that it is bowed outwardly (as in Figure 2) or inwardly. The closure is made of spring metal so that disk 10 is in reality a two-way detent spring which tends to hold its position when pressed to one side or the other of the plane of the fulcrum-ring 12. It is readily apparent that when disk 10 is pressed inwardly, fingers 11 will move outwardly rotating about the fulcrum 12 and so release the closure from the container. If the fingers 11 are now pressed inwardly against the container, disk 10 will be swung outwardly about fulcrum 12 to its 55 Figure 2 position, and, being a two-way

spring as described above, will hold fingers 11 in their gripping position. If the container is provided with a rib 13 adjacent the opening, the fingers 11 may be bent under as at 14 to more firmly grip the rib.

In packing or transporting the container there is a possibility that disk 10 will be pressed inwardly and the container will thus be uncovered, or at least the fingers 11 will be moved to ineffective positions enabling the cover to be readily removed. Moreover the covers may be readily removed for fraudulent purposes such as filling the container with inferior material. To obviate these objections there is provided a flexible metal strip or band 20 which may be drawn around the fingers 11, said strip being provided with a tongue 21 near one end which is drawn through an opening 22 in the other end so that the ends of the band 75 may be drawn together. By bending the tongue back on itself, the flexible band is locked tightly about the fingers 11 which are thus prevented from moving to open or closed positions. The tongue may be so constructed that by merely bending it back once to open the band, it will break off, thus betraying fraudulent opening.

If the container is provided with a rib 13 and the fingers 11 are bent under as at 14, 85 the flexible band may be similarly bent under as at 24 to grip under the curved ends 14, and may also be bent over the top of the fingers and rib as at 25. The result is that when the band is locked in position around the cap it cannot move vertically with respect thereto, and consequently cannot come off accidentally; so that the cap once gripped and banded in place cannot be removed until the band is taken off.

The above description illustrates a preferred form of my device, but it is understood that various changes may be made within the scope of the annexed claims.

I claim:

1. In combination, a container, said container having a shoulder, a self gripping and releasable cap closure fitting over the opening of said container and having depending spring fingers engaging under said shoulder, 105 a band enclosing the depending fingers to hold them in gripping relation to the shoulder, said band having a flange extending under the shoulder and a second flange extending over the top of the closure where- 110

by accidental displacement of the closure is prevented.

2. In combination, a container, said container having a shoulder, a closure for said container, said closure having a central portion for covering the opening and resting upon said container to form a fulcrum, and having fingers depending from said central portion to grip the shoulder, said central portion being swingable about said fulcrum

to swing said fingers out of gripping relation with said shoulder, a flexible band surrounding said fingers to hold them in gripping relation to the shoulder, said band having a flange extending under the shoulder and a second flange extending over the top of the closure whereby accidental displacement of the closure is prevented. ¹⁵

In testimony whereof I affix my signature.

HERBERT T. SNYDER.
